UNITED STATES PATENT OFFICE.

HENRY T. EMEIS, OF SALT LAKE CITY, UTAH.

EAR-LABEL.

SPECIFICATION forming part of Letters Patent No. 700,483, dated May 20, 1902.

Application filed August 29, 1901. Serial No. 73,713. (No model.)

To all whom it may concern:

Be it known that I, HENRY T. EMEIS, a citizen of the United States, residing at Salt Lake City, in the county of Salt Lake and State of Utah, have invented a new and useful Ear-Label, of which the following is a specification.

This invention relates to stock-marking tags, and more particularly to that class that are attached to an animal's ear and bear identifying marks or characters, such as the name of the owner or his private brand.

The object of the invention is to provide a stock-marking tag which may be readily attached to the animal's ear and which when once associated therewith will be firmly held from disengagement.

A further object is to provide a simple and efficient means whereby a pendant or check may be associated with the tag, said pendant to contain a mark, such as the brand-mark of the cattle or other stock to which the device is attached or the name or initial of the owner.

A further object is to provide a stock-marking tag of the character specified in which the ear cutting or piercing portion will be so constructed as to insure prompt and effective piercing of the animal's ear and to prevent unnecessary pain to the animal.

With these and other objects in view, as will appear in the presentation of the case, the invention consists in the novel construction and combination of parts of a stock-marking tag, as will be hereinafter fully described and claimed.

Generally stated, the invention comprises a strip of metal bent upon itself in approximate V shape and carrying on one member a punch or cutting-ferrule suitably held associated with the member by a combined eyelet and rivet, the end of the rivet to pass through an orifice in the other member and to be clenched on top thereof, thereby to hold the two members firmly assembled. The eye portion of the rivet is to have associated with it a pendant or check to bear an initial, brand-mark, or any other printed matter or mark to indicate the owner of the cattle. The device as a whole is of great simplicity of construction and may be readily applied to an animal's ear without unnecessary pain, and when once so attached will be a perma-

nent fixture, being securely held against any possibility of accidental separation.

In the accompanying drawings, forming a part of this specification, and in which like numerals of reference indicate corresponding parts, I have illustrated one form of embodiment of my invention, it being understood that the ideas therein illustrated may be modified or changed without departing from the spirit of the invention, and in these drawings—

Figure 1 is a view of an animal's head, showing the tag attached thereto. Fig. 2 is a view in perspective of the tag detached. Fig. 3 is a view in longitudinal section exhibiting more particularly the operative relation existing between the parts. Fig. 4 is a detail perspective view of the combined rivet and eyelet. Fig. 5 is a detail perspective view of the clip member of the device. Fig. 6 is a detail perspective view of the cutting thimble or ferrule.

Referring to the drawings, 1 designates the body of the tag, the same being constructed of a thin strip of metal, which may be steel, tin, aluminium, or any other suitable material, soft tinned steel being preferable on account of its strong and non-corrosive qualities. The strip of metal is bent upon itself to present a substantially V-shaped clip, the opposite ends of which are provided with the corresponding transverse slots 2 and 3, respectively, of which the slot 2 is the longer. For the connection of the opposite free ends of the clip there is provided a pin or rivet 4, which is first inserted through the long slot 2 and finally into the other slot 3. The intermediate body portion of this rivet is broad and flat, so as to snugly fit the slot 2, and has one end reduced and pointed, as at 5, to enter the smaller slot 3 and also to pierce the ear of an animal, the projected end of the pointed portion being bent over or upset against the outer side of the adjacent member of the clip or body 1, as indicated at 6, so as to prevent endwise movement of the rivet in one direction. The opposite end of the flat body portion has opposite lateral projections 7, which constitute a head to lie against the outer side of the adjacent member of the clip, and thereby limit the inward insertion

of the rivet, there being an open hook or eyelet 8 formed at this head end of the body. As clearly indicated in Fig. 4, it will be seen that this combined rivet and eyelet is designed to be formed from a flat piece of metal, thereby to provide a strong, durable, and inexpensive fastening device.

Located between the members of the clip is a substantially cylindrical open-ended thimble or ferrule 9, which embraces the intermediate portion of the rivet or fastening device and also forms a stop which limits the inward movements of the members of the clip. That end of the ferrule or thimble 15 which is adjacent to the pointed end of the rivet is provided with a sharp marginal edge 10, which is designed to form a cutter.

It will be understood that it is designed to have a suitable inscription upon the body or 20 clip, so as to identify the animal to which the tag is applied, and in addition to this it is designed to provide a pendant or tag proper, 25 bearing the owner's name, mark, or other indicating character, there being an eye or perforation 12 formed in the tag and designed for the reception of the split ring or eyelet 8, whereby the tag or pendant may be loosely connected to the body or clip.

In attaching the device to an animal's ear 30 suitable pliers are employed, having in one jaw a depression to receive the split ring or eyelet 8 and the opposite jaw having a flat surface against which the point of the rivet is adapted to bear. The members of the U-shaped body are first spread, the pendant being placed upon the eyelet, after which the rivet is inserted into the slot 2 and the thimble or ferrule is placed between the clip members and upon the inner end of the rivet. 35 The clip is then placed astraddle of the ear of the animal, and the pliers are applied to the clip and operated to press together the opposite sides of the clip, thereby forcing the rivet and the thimble or ferrule through the 40 ear, upsetting the pointed end of the rivet against the adjacent outer side of the clip and also closing the split ring or eyelet, whereby the device is conveniently attached to the animal, and the pendant or tag is secured to 45 the clip, all of which is accomplished by one operation of the pliers. When thus secured in position, it will be impossible to detach the tag from the animal's ear without destroying some portion of the tag, either the 50 upset portion of the rivet or the clip or body itself.

The purpose of the substantially cylindrical thimble or ferrule is to provide a rounded or substantially circular bearing for the connection between the animal's ear and the device, whereby it is possible for the bearing to turn within the opening formed in the ear and in any event to prevent tearing or injury to the ear by movement of the device.

55 In applying the tag to an animal's ear the pendant is disposed upon the inside of the

ear, thereby to prevent it catching upon brush, bushes, or the like when the animal is feeding.

Although the tag member illustrated in the drawings is shown as made of metal and having a mark or character cut or stamped therein, it will be understood that it is also designed to provide tags of some strong, durable, and flexible material having the distinguishing mark or character printed or otherwise applied thereto and also provided with a suitable eyelet for engagement with the split ring of the rivet or fastening device. Moreover, although the clip member has been shown and described as V-shaped it may also be of substantially U shape, as the essential object is to have the clip composed of a pair of members to straddle the ear of an animal in substantially the manner shown in the drawings, so as to secure an effective engagement of the clip with the ear.

From the foregoing it is thought that the construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages of the invention.

What I claim is—

1. An ear-label, comprising a two-membered clip having corresponding perforations, a fastening to be projected through the perforations, one end of the fastening being pointed and adapted to be upset against one outer side of the member, and a tag carried by the opposite end of the fastening. 100
2. An ear-label comprising a tag, a cutting-ferrule carried thereby, and a combined eyelet and rivet for holding the ferrule assembled with the tag. 105
3. An ear-label comprising a tag, a cutting-ferrule carried thereby, a rivet for holding the ferrule assembled with the tag, an eyelet on the rivet, and a pendant engaging the eyelet. 110
4. An ear-label comprising a two-membered tag, a cutting-ferrule carried by one of the members of the tag, and a pointed rivet passing through the ferrule and through the other member of the tag to hold the two members assembled. 115
5. A device of the character described, consisting of a substantially V-shaped clip having opposite corresponding perforations, a pointed fastening to project through the perforations, one end of the fastening having a head to limit the inward movement thereof, and the opposite end being constructed to be upset against the adjacent outer side of the clip, and means for connecting a tag member to the headed end of the fastening. 120
6. A device of the character described, comprising a substantially V-shaped clip having terminal corresponding slots, one of which is 125

longer than the other, and a flat fastening device to be inserted endwise through the long slot and finally the other slot, the intermediate portion of the fastening being flat and having one end reduced and pointed, the opposite end being enlarged to form a head for limiting the inward insertion of the fastening, the pointed end of the latter being constructed to be upset against the adjacent outer face of the clip.

7. A device of the character described, comprising a substantially V-shaped clip having corresponding terminal perforations, a cutting-ferrule located between the members and aligned with the corresponding perforations, a fastening device to be inserted through the

perforations and the ferrule, one end of the fastening being pointed and adapted to be upset against the outer face of the adjacent portion of the clip, and the opposite end of the fastening having a split ring, and a tag having an eyelet for engagement with the split ring.

In testimony that I claim the foregoing as my own I have hereto affixed my signature in the presence of witnesses.

HENRY T. EMEIS.
